E. Ripley, Troy, N. Y. Letters Patent No
193, dated August 10th 1845. (Assigned to Johnson & Co.)

The Schedule referred to in these Letters Patent and
making part of the same

To all to whom these presents shall come: Be
it known that I, Ezra Ripley of Troy in the County of
Rensselaer and State of New York have invented or produced
a new design for stone plates, and that the following is a
full, clear and exact description of the same, reference
being had to the accompanying drawings, making part of
this specification, in which Fig. 2. is a view of the front
plate of an "American Cottage Air Tight" Parlor Stove.
This plate as shown in the drawing is ornamented in the
centre with a carved tablet about two inches in width mark-
ed fig 3 and directly above the same is a carved moulding
and on either end of said plate is a Gothic niche marked
Fig. 4. I claim as my invention and desire to secure by
Letters Patent the above design which is fully set forth
in the drawings accompanying this description
